UNITED STATES PATENT OFFICE.

WILLIAM R. WILLIAMS, OF OWENSBORO, KENTUCKY, ASSIGNEE, BY MESNE ASSIGNMENTS, TO OWENSBORO DITCHER AND GRADER COMPANY, OF OWENSBORO, KENTUCKY, A CORPORATION OF KENTUCKY.

ROAD-GRADING MACHINE AND DITCHER.

1,129,936.

Specification of Letters Patent.

Patented Mar. 2, 1915.

Application filed April 1, 1914. Serial No. 828,716.

To all whom it may concern:

Be it known that I, WILLIAM R. WILLIAMS, a citizen of the United States, residing at Owensboro, in the county of Daviess 5 and State of Kentucky, have invented a new and useful Road-Grading Machine and Ditcher; and I do hereby declare the following to be a full, clear, and exact description of the invention, such as will enable others 10 skilled in the art to which it appertains to make and use the same.

This invention relates to a new and useful improved road grading machine and ditcher, and an object of the invention is the 15 provision of a machine of this nature involving improved features of construction in the provision of a concave blade extending diagonally from the machine, and provided with holders at its outer end to receive an 20 extension blade. This blade and its extension constitutes means for scraping and leveling the road-bed, the concave blade being of sufficient height to prevent the dirt and the like crowding over the top of the 25 same.

A feature of the invention is the fact that after one side of the road-bed has been graded or leveled, the entire machine may be completely turned over end for end, so 30 as to grade or level the other side of the road-bed.

Another feature of the invention is that by turning the machine over, the dirt and the like is always thrown in the same direction to one side of the road.

Another feature of the invention is the fact that the blade and its extension are adjustable angularly with relation to the machine.

40 In practical fields the details of construction may necessitate alterations, falling within the scope of what is claimed.

The invention comprises further features and combination of parts, as hereinafter set 45 forth, shown in the drawings and claimed.

In the drawings:—Figure 1 is a plan view of the improved machine. Fig. 2 is a side elevation. Fig. 3 is a sectional view on line 3—3 of Fig. 1. Fig. 4 is a detail view of the 50 blade and its extension. Fig. 5 is a detail view showing a modified form of the structure shown in Fig. 3.

Referring more especially to the drawings, 1 designates an elongated guide member,

which may be constructed of metal or wood or any other suitable material. The forward end of this member 1 has bolted to it the two sides of the metal strap 3. The two sides of said strap are designated by the numeral 2, and the bolts are denoted by the numeral 4. Where the strap 3 is bent upon itself to form the two sides a recess 5 is constructed, in which one end of the bar 6 is pivoted by means of the pin 7. This bar 6 is provided with a clevis member 8, connected at 9 thereto. On one face of the plate or bar or member 1 staples 10 are provided, to which the blade 11 is pivoted. This blade at one end is concaved, as shown, and which concavity gradually vanishes toward the end 12 of the blade. The blade 11 is braced by the reinforcing strip or angle member 14, secured upon the rear face. Pivotally mounted in the straps 15 of the rear face of the blade 11 are the ends of a link loop 16, which is pivoted to the connecting rod 17. The end 18 of the rod may be connected by means of a bolt 19 to any one of the eyes 20 of the elongated plate, board or member 1, so as to hold the blade 11 adjustably at different angles to the member 1. In cutting a ditch, the blade 11 is designed to be held at an acute angle to the member 1, in such a position as shown at *a* in Fig. 1. On the rear face of the blade 11 adjacent its outer end a metal strap 22 is secured. This strap is constructed with arches 23 and 24, in either one of which and adjacent the blade, one end of the extension blade 25 is arranged. The outer end of the extension blade is provided with the usual shoe 26. In grading a road-bed, the extension blade is employed, and the blade 11 is adjusted farther outwardly and from the member 1. After the machine has traveled the road in one direction, the same may be completely turned over, and the extension blade adjusted in the arch 24, and the machine may then be returned along the road-bed, thereby throwing the dirt on the same side of the road-bed. However, in returning the machine, the same may be moved toward the side of the road-bed, that is, nearer to the side, than when traveling in the first direction. A link 27 is connected to the blade 11, and has its end portion 28 connected to any one of the apertures 29 of the bar 6. Draft animals may be connected to the

clevis 8 in any suitable manner (not shown), and the pulling upon the bar 8 assists in maintaining the blade 11 in position.

A platform 30 is supported at right angles to the member 1, by means of the brackets 31, which are provided with hooked ends 32 engaging the member 1, in the manner shown in the drawing, particularly as shown in Fig. 3. This platform 30 constitutes means on which the operator may stand, in operating the machine. The rear end of the member 1 is provided with runners 33 and 34, bolted at 35. When the machine is moving in one direction the runner 34 engages the road-bed, but when traveling in the reverse direction, the runner 33 engages the road-bed.

As a rule, in grading a road, the greater part of the dirt crowds against the scraper blade adjacent the land side or guide member, the dirt gradually tapering or grading down toward the outer end of the blade. Therefore by constructing the blade of heavy sheet metal, and making the same concaved, adjacent where the blade is connected to the land side or guide member 1, the greater portion of the dirt is prevented from crowding over the top of the blade, and owing to the scraped dirt gradually grading or tapering toward the outer end of the blade, it has been found essential and practical to provide a blade, in which the concavity of the same gradually merges into a straight portion. The straight portion of the blade beyond the diminished concavity of the blade is allowed to flex or bend very slightly. It has been found in practice, that if the blade is not suitably reinforced, the same will abruptly bend substantially at the junction where the concavity of the blade blends into the straight portion thereof, hence it has been found by placing a reinforcing member angular in cross section, such as that indicated at 14, this abrupt bending will be prevented. As hereinbefore described a connection 27 is provided between the bar 6 (to which any suitable equalizer may be connected) and the scraper blade, which connection 27 acts to hold the loose connections 16 and 17 taut. It has been found in practice that when the scraper blade contacts with an obstruction, thereby pulling back upon the horse power (which may be connected to the bar 6), the loose links 16 and 17 will collapse, allowing the blade to yield. When the blade yields in this manner, the link 16 is allowed to swing upon a substantially full half arc, which will permit the blade to yield sufficiently, un-

til it either removes the obstruction or passes over the same; in either case the horse power will straighten both link connections, thereby relieving all jars and jerks on the body or land side member, and the operator on the platform.

The extension blade 25 may be inserted in either of the arches 23 and 24, as hereinbefore stated, the same being forced into place, and held therein by friction. Furthermore, even though the extension plate 35 is forced in either one of the arches 23 and 24, the same may be adjusted inwardly or outwardly, which affords another advantage, in that where the blade 11 cannot be adjusted through the mediums of the links 16 and 17 (that is, when the said extension blade 25 is carried thereby) to grade a certain width of road, the extension blade may be adjusted to accommodate the width of the road, that is, slidably adjusted. Another advantage in forming the outer ends of the blade 11 straight, and the concavity gradually merging therewith, is that when adjusting the extension blade 25, the portion which is received in the arch will be flat against the straight portion of the blade 11.

From the foregoing it will be observed that an improved road grading and ditching machine is provided, and one which can be used for throwing the dirt always to the same side of the road-bed.

The invention having been set forth, what is claimed as new and useful is:—

In a road grading machine, a land side body member, a scraper blade connected at its forward end to the forward portion of the body member and extending laterally and rearwardly at an angle to the body member, connections between the rear lateral end of the blade and the body member, said scraper blade being concaved rearwardly where it connects to the body member, said concavity gradually diminishing and blending laterally and rearwardly toward the outer portion of the blade, said blade adjacent its outer portion being vertically straight and flat, and a reinforcing bar reinforcing the blade at the junction where the concavity merges into the flat vertically straight portion.

In testimony whereof I have signed my name to this specification in the presence of two subscribing witnesses.

WILLIAM R. WILLIAMS.
